UNITED STATES PATENT OFFICE.

WILLIAM D. JAMES, OF FORT ATKINSON, WISCONSIN.

STANCHION.

1,081,045

Specification of Letters Patent.

Patented Dec. 9, 1913.

Application filed November 26, 1903. Serial No. 525,280.

To all whom it may concern:

Be it known that I, WILLIAM D. JAMES, a citizen of the United States, residing at Fort Atkinson, county of Jefferson, and 5 State of Wisconsin, have invented new and useful Improvements in Stanchions, of which the following is a specification.

My invention relates to improvements in stanchions, and it pertains more especially, 10 among other things, 1st. to the device for simultaneously closing and opening all of the stanchions from one side of the inclosure, and 2nd. to the device for releasing any one or more of the stanchions independently of the others.

The construction of my invention is explained by reference to the accompanying drawings, in which—

Figure 1 is a front view of the stanchion 20 and stanchion supporting frame. Fig. 2 is a detail, part broken away, showing a portion of a stanchion supporting frame, one of the stationary vertical members and one of the movable stanchion members in connection 25 with a portion of the upper horizontal member. Fig. 3 is a detail, part in section, of the view shown in Fig. 2. Fig. 4 is a detail, showing a side view of one of the adjustable members in connection with the top frame member, and Fig. 5 is a detail of the view shown in Fig. 4, drawn at right angles thereto.

Like parts are identified by the same reference numerals throughout the several views.

My device comprises among other things a series of adjustable stanchions 9, inclinable stanchions 10, intermediate stationary members 11 and horizontal members 12 and 13, all of which parts are preferably formed of ordinary metallic tubing, and said stanchion and intermediate members are respectively supported at their lower ends from said horizontal members 12 and at 45 their upper ends from said horizontal member 13, and said horizontal members are supported at their respective ends from the posts 14, 14', and at intermediate points by the posts 14" and 14'.

50 Referring to Fig. 1, the upper horizontal member 13 is connected with the vertical posts 14 and 14', by the clamping plates 15, 15', and clamping bolts 15", while the lower horizontal member 12 is connected with said

posts by the clamping plates 16, 16 and 55 clamping bolts 16'. The posts 14 are connected with the floor 17 by the sockets 18 and bolts 19, or in any convenient manner. The adjustable stanchion members 9 are connected at their respective ends to the 60 lower and upper horizontal members 12 and 13 by the clamping Ts 20, 20. The Ts 20 are respectively formed of a single piece of flexible metal, the central portion of which is bent to form the circular member 21, 65 which is adapted to surround and inclose the horizontal members 12 and 13, while the respective ends 22 of said loop are bent to conform to the surface of the adjustable stanchion member 9, when said ends are 70 rigidly secured together around said horizontal and vertical members by the clamping bolt 23. Thus it will be obvious that by releasing the nut 25' on said bolt, said 75 members may be sprung slightly at rt, whereby the stanchion members may be adjusted longitudinally on said horizontal members 12 and 13 at any desired distance from the inclinable stanchion members 10 to conform to the necks of the calves re- 80 tained between said stanchion members.

The inclinable stanchion members 10 are pivotally connected at their lower ends with said horizontal member 12 by the vertical pins 24, which have bearings in the sockets 85 or apertures 24' provided therefor in the upper sides of said horizontal members, while the upper ends of said inclinable stanchion members 10 are connected with metallic brackets 25, by the integrally 90 formed trunnions 26, which are closely fitted in the upper ends of said stanchion members. The brackets 25 are provided with circular openings 27, for the reception of the longitudinal member 13 and circular 95 openings 28, for the reception of a longitudinal locking bar 29. The locking bar 29 is slidably supported at intervals above the horizontal member 13 by the clamping plates 30, between the bolts 31, 31, and said 100 locking bar 29 is provided with a series of transversely arranged pins 32, which serve as stops to limit the movement of the inclinable stanchion members as they are brought to the vertical. The locking mem- 105 ber 29 is also provided on its upper side with a series of notches 33, for the reception of the lower end of the locking pin 34,

which pin 34 is slidably connected with the upper side of the bracket 25, whereby all of the inclinable stanchions 10 of the series may be simultaneously closed and opened by the longitudinal movement of the locking bar 29.

It will be understood that when the locking pins 34 are all in the notches 33 and the locking bar 29 is drawn toward the left to the position shown in Fig. 1, all of said inclinable stanchion members 10 will be brought to the vertical closed position, as shown in said Fig. 1. When, however, said locking bar 29 is moved toward the right or in the opposite direction, all of said inclinable stanchion members will be inclined toward the right or open position, as indicated by dotted lines in said Fig. 1, motion being communicated to said inclinable stanchion members from said locking bar through said brackets 25 and locking pins 34.

For convenience of operating the locking bar 29, I have provided an operating handle 35, which operating handle is pivotally supported at one end from the horizontal member 13 by the clamping plates 30 and pivotal bolt 36, while it is connected to the end of said locking bar 29 by a pivotal bolt 37, link 37 and pivotal bolt 40. Thus it will be obvious that when the operating lever 35 is moved from the position shown in Fig. 1, to that indicated by dotted lines in said figure, all of said inclinable stanchion members 10 will be inclined toward the right as indicated by dotted lines in said Fig. 1, when by a reverse movement of said lever 35, said inclinable stanchion members will be brought back and retained in their vertical position, as shown in said figure, when owing to the fact that the locking bar 29 is connected with said operating lever at a point below the supporting pivot 36, when the stanchions are in their locked position, any lateral strain brought to bear against the movable stanchion member will have a tendency to draw said lever 35 downwardly more firmly against the supporting stop, whereby said operating lever serves as a lock for retaining the inclinable stanchions in their closed position, as well as the means of operating them, and the liability of said stanchions being opened by lateral pressure is avoided.

The stationary members 11 are connected at their lower ends with the horizontal members 12 and 13 by the vertical pins 38, said pins 38 being rigidly affixed at one end to said stationary members 11, while their opposite ends are secured in apertures 39 provided therefor in the sides of said horizontal members 12 and 13. It will be understood that for convenience of construction, the horizontal members 12 and 13, the connecting posts 14, intermediate posts 14', the several stanchion members 9 and 10, and

intermediate vertical members 11, are all preferably made of ordinary tubing, whereby the maximum strength is provided with a minimum weight of material.

While I have shown and described a means of operating all of the inclinable stanchion members at the same time, it will be understood that any one of said inclinable stanchion members may be opened independently of the others by manually withdrawing the locking pins 34 from their retaining recesses 33 and that any one of such inclinable stanchion members may be manually closed by moving the same from the inclined to the vertical position, when said locking pins 34 will drop of their own gravity into the retaining recesses 33 of the locking bar, whereby the stanchion will be retained in place.

It will be understood that by the device described, a plurality of calves or other animals may all be simultaneously secured in place by moving the lever 35 from the position indicated by dotted lines in Fig. 1 to the position shown in that figure. When, however, it is desirable to release such animals from the stanchions, all of said stanchions may be simultaneously opened by reversing the movement of said lever, as previously described.

Having thus described my invention, what I claim as new, and desire to secure by Letters Patent, is—

1. In a device of the described class, the combination of a stanchion supporting frame, comprising a pair of stationary horizontal members, and a plurality of vertical members rigidly affixed at their respective ends to said horizontal members, a plurality of pairs of stanchions supported by said frame, each pair comprising a vertical member and an inclinable member, means for simultaneously moving all of said inclinable stanchion members to either their open or closed position and for simultaneously locking all of said members in their closed position, and means for disengaging any one of said inclinable members from the operating means whereby such inclinable member may be operated independently of all the others.

2. In a device of the described class, the combination of a stanchion supporting frame, comprising a pair of stationary horizontal members, and a plurality of vertical members rigidly affixed at their respective ends to said horizontal members, a plurality of pairs of stanchions supported by said frame, each pair comprising a vertical member and an inclinable member, a slideable bar horizontally supported above said frame provided upon its upper edge with a plurality of notches, the upper end of each of said inclinable stanchion members being provided with a vertically movable pin adapted to detachably engage in one of the notches

of said slidable member, a plurality of transversely arranged stops projecting from the sides of said slidable bar and adapted to limit and stop the movement of the inclinable stanchion members when they reach the vertical, a handle pivotally connected at one end with said stationary supporting frame and at an intermediate point between its

ends with said slidable member, all substantially as and for the purpose specified.

In testimony whereof I affix my signature in the presence of two witnesses.

WILLIAM D. JAMES.
